UNITED STATES PATENT OFFICE.

WILLIAM F. LEACH, OF ST. CLAIR, MICHIGAN, ASSIGNOR TO HIMSELF AND CROCKET MCELROY, OF SAME PLACE.

PORTABLE STEAM-AUGER.

SPECIFICATION forming part of Letters Patent No. 244,629, dated July 19, 1881.

Application filed May 11, 1881. (No model.)

To all whom it may concern:

Be it known that I, WILLIAM FRANCIS LEACH, of St. Clair, in the county of St. Clair and State of Michigan, have invented a new and useful Improvement in Portable Steam-Augers, of which the following is a specification.

Figure 1 is a plan view of my improvement. Fig. 2 is a rear elevation of the same. Fig. 3 is a side elevation of the same. Fig. 4 is a sectional rear elevation of the same, taken through the line $x-x$, Fig. 1.

Similar letters of reference indicate corresponding parts.

15 The object of this invention is to facilitate the boring and drilling of wood and metal.

The invention consists in constructing a portable steam-auger with a rotary steam-engine to operate the boring-tool, handles for carrying and holding the engine, a breastplate for forcing the boring-tool forward to its work, and a tool holder or coupling for connecting a boring-tool with the engine, as set forth.

25 A represents the shell of a rotary steam-engine, which is made small and light, so that it can be conveniently carried.

In an aperture in the upper side of the shell A is secured a short pipe, B, to receive a flexible pipe or hose, through which steam is introduced into the engine, and which is designed to be provided with a valve for controlling the admission of steam.

30 In an aperture in the lower side of the shell A is secured a short pipe, C, to receive a flexible pipe or hose, through which the exhaust steam escapes.

Within the shell A are placed revolving pistons or wheels D, which are revolved by the inflowing steam, and about the construction 40 of which there is nothing new.

To the projecting forward end of the journals or shafts of the rotary pistons D are attached two gear-wheels, E, the teeth of which mesh into each other, so that the rotary pistons D will be compelled to revolve with the 45 same velocity.

To the upper and lower sides of the shell A are attached cross-bars F, the ends of which project at the sides of the shell A, and have rounds G attached to them. The cross-bars 50 F and rounds G form handles, by which the machine can be conveniently carried and held while being used.

H is the breastplate for the body of the operator to rest against when using the auger to 55 force it forward into the timber or metal being bored or drilled. The breastplate H is provided with arms I, which project forward and are attached to the cross-bars F.

To the forward journal of one of the rotary 60 pistons D is attached a coupling, J, to receive an auger when the machine is to be used for boring wood, and to receive a drill when the machine is to be used for boring metal. The shank of the boring-tool is secured in the coupling or holder J by a set-screw, K, or other suitable means.

Having thus fully described my invention, I claim as new and desire to secure by Letters Patent—

The combination, with a steam-engine, A B C D, having the coupling J K, of the cross-bars F, rounds G, and breastplate having arms I, to form a portable engine which may be held to the breast while the auger is operated by 75 steam, as described.

WILLIAM FRANCIS LEACH.
